UNITED STATES PATENT OFFICE.

THOMAS WASHINGTON MILLER, OF WASHINGTON, DISTRICT OF COLUMBIA.

DESIGN FOR AN OIL-CUP.

SPECIFICATION forming part of Design No. 33,252, dated September 25, 1900.

Application filed July 30, 1900. Serial No. 25,364. Term of patent 3½ years.

To all whom it may concern:

Be it known that I, THOMAS WASHINGTON MILLER, a citizen of the United States, residing at Washington city, in the District of Columbia, have invented a certain new and useful Design for an Oil-Cup; and I do declare the following to be a full, clear, and exact description of the invention, such as will enable others skilled in the art to which it appertains to make and use the same.

My invention relates to a new and useful design for an oil-cup for vehicle-axles, and the figure in the accompanying drawing is a perspective view of an oil-cup for vehicle-axles embodying my design and which is the subject-matter of my invention.

The essential features of my design are the cylindrical stem formed with threads on its lower or free end, terminating at its opposite

end in the enlarged cylindrical body ²⁰ surmounted by the flat circular cap which projects over the walls of the body portion and having a rectangular boss centrally fixed on its face.

Having thus fully described my invention, ²⁵ what I claim as new and useful, and desire to secure by Letters Patent of the United States, is—

The design for an oil-cup substantially as herein shown and described. ³⁰

In testimony whereof I have hereunto set my hand in presence of two subscribing witnesses.

THOMAS WASHINGTON MILLER.
